(57) CLAIM

The ornamental design for a container for perfumes and cosmetic products, as shown and described.

DESCRIPTION

FIG. 1 is an exploded side top perspective view of a container for perfumes and cosmetic products showing my new design;

FIG. 2 is a front elevational view thereof;

FIG. 3 is a rear elevation view thereof, being a mirror image of the front elevation view of FIG. 2;

FIG. 4 is a left side elevation view thereof;

FIG. 5 is a right side elevation view thereof, being a mirror image of the left side elevation view of FIG. 4;

FIG. 6 is a top plan view thereof; and,

FIG. 7 is a bottom plan view thereof, with the broken lines in FIG. 7 being for illustrative purposes only and forming no part of the claimed design.
